VENDABLE DISPENSING CONTAINER FOR ROLL OF GUMMED LABELS OR THE LIKE

Ernest W. Friday, Somerton, Pa., assignor to Tompkins' Label Service, Philadelphia, Pa., a corporation of Pennsylvania

Application June 7, 1951, Serial No. 230,395

11 Claims. (Cl. 281—6)

The present invention relates generally to dispensing containers for rolls of gummed labels or the like.

An object of the present invention is to provide a new and improved construction for a dispensing container for a roll of gummed labels or the like. Another object of the present invention is to provide an inexpensive and easy-to-manufacture vendible container for holding a roll of gummed labels or the like which will enable the user to write upon, or stamp, individual labels and thereafter to tear off the individual labels quickly and easily.

Other objects and advantages of the present invention are apparent from the following detailed description, appended claims and accompanying drawings.

Gummed labels are conventionally manufactured and sold in rolls with transverse lines of perforations facilitating the tearing off of the individual labels.

However, these rolls of gummed labels, when exposed, very often become sticky due to inadvertent moistening or wetting of the adhesive such as makes them messy to handle and frequently causes the top layer of labels to adhere to the underlying layer, thereby making it difficult or impossible to remove individual labels as desired.

Additionally, these rolls of gummed labels tend to become unwound, quite readily, which results in the labels becoming soiled or crumpled. Furthermore, since most gummed labels are printed wholly or partly in blank (i.e., with space left thereon for writing or stamping such data as the name of the product, the weight, the price, etc.), the filling in of the labels presents a problem. That is, where a grocer or other merchant has to tear off and then fill in (by writing or stamping thereon) large numbers of individual labels, the backs of the labels, as well as the hands of the user, soon become sticky so that the labels become soiled and tend to stick to the underlying surface, thereby resulting in very appreciable loss in time and energy.

According to the present invention, there is provided, for the first time, a simple and inexpensive vendible container for a roll of gummed labels or the like which will hold the roll of gummed labels in generally enclosed position and which will successively expose individual labels in position to be written or stamped upon and which will thereafter quickly and easily dispense the individual labels, as needed.

Generally speaking, the present invention contemplates a novel construction for a box or the like, of cardboard or other similar inexpensive material (which may be provided with edge-reinforcements), provided with slits or openings or windows enabling individual labels to be exposed successively prior to reaching a disconnecting edge or surface so that the user can manually move each label into position to be written or stamped upon and thereafter move it to a position to be severed, at the same time moving the next label into position to be written upon.

For the purpose of illustrating the invention, there

2

are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a perspective view of one embodiment of the present invention as it appears in use.

Figure 2 represents a cross-sectional view generally along the line 2—2 of Figure 1.

Figure 3 represents a perspective view generally like that of Figure 1 but showing the cover or lid in partly open position.

Figure 4 represents an exploded view of the embodiment of Figures 2—3 showing the box in fully-opened position and showing the roll of gummed labels and the insert member or tray in position to be inserted within the box.

Figure 5 represents a perspective view of another embodiment of the present invention as it appears in use.

Figure 6 represents a cross-sectional view generally along the line 6—6 of Figure 5.

Figure 7 represents a cross-sectional view generally along the line 7—7 of Figure 5.

Figure 8 represents a perspective view of the embodiment of Figure 5 but with the cover or lid shown in open position.

Figure 9 represents an elevational view taken generally from the top of Figure 5 showing the box or container as it appears before the insertion of the roll of gummed labels.

Figure 10 represents a perspective view of still another embodiment of the present invention as it appears in use.

Figure 11 represents a perspective view of the embodiment of Figure 10 as it appears when turned half-way around and with the cover or lid shown partly open.

Figure 12 represents a cross-sectional view generally along the line 12—12 of Figure 10.

Figure 13 represents an elevational view looking generally from the top of Figure 10 showing the appearance of the box or container before insertion of the roll of gummed labels.

In Figures 1—4, there is shown one embodiment of the present invention which includes a box or container 20 which may be integrally formed from a sheet of cardboard or other inexpensive relatively form-retaining material appropriately cut, folded and glued in a manner to be described more fully hereinbelow. The box 20 may optionally (but not necessarily) have the form of a cube and may include a top wall 21 having a generally rectangular window 22 therein, side walls 23, 24 and 25, a bottom wall 26 and a side cover or lid 27 formed in continuation of the side wall 23 and having a generally vertical hinge-line 28.

The cover or lid 27 may be provided with top and bottom tuck-in flaps 29 and 30 and a side tuck-in flap 31.

The top and bottom walls 21 and 26 may be provided with flaps 32 constructed and arranged to be tucked inside of, and pasted to, the side walls 23 and 25 so as to form the box; the top and bottom walls 21 and 26 and the side walls 23 and 25 all being formed in continuation of the side wall 24. The free edge of the side wall 25 is notched as at 33 to facilitate opening and closing of the cover or lid 27.

A separate, generally U-shaped insert-member 34 is provided for the box 20. The insert-member 34 includes a top wall 35 and side walls 36 and 37. The vertical dimension of the side walls 36 and 37 is just slightly less than

the vertical dimension of the corresponding side walls 23 and 25 of the box 20 so that the top wall 35 of the insert-member 34 is maintained in juxtaposition to the top wall of the box 20. The top tuck-in flap 29 preferably fits underneath the top wall 35 of the insert-member 34 when the cover or lid 27 is closed, as indicated particularly in Figure 2, so as to provide added support for the top wall 35. The side tuck-in flap 31 fits outside of the side wall 37 of the insert-member 34 as indicated particularly in Figure 1.

The horizontal dimension of the walls of the insert-member 34 is somewhat less than that of the walls 21, 23, 25 and 26 of the box 20 so that there is a little clearance intermediate the inner edge of the top wall 35 and the side wall 24.

A roll 38 made up of individual labels 39 separated by transverse lines of perforations 40 is constructed and arranged to be inserted within the box 20 with the roll 38 underneath the top wall 35 of the insert-member 34 and intermediate the side walls 36 and 37. The free end of the roll 38 passes upward and over the inner edge of the top wall 35, and extends across the top wall 35 so that it is visible within the window 22.

The edge 41 of the window 22 which is nearest the free edge 42 of the top wall 21 is provided with an integrally-formed inturned lip 43 which bears against the adjoining edge of the top wall 35, as shown particularly in Figure 2, so as to provide a shearing-surface for severing individual labels, as will be described hereinbelow. As shown particularly in Figure 4, small supporting ears 44 are provided at the ends of the lip 43.

The dispensing container 20 of this embodiment is operated by first positioning a label so that it is centered with respect to the window 22, in the manner shown in solid lines in Figure 1. In this position, the major portion of the label is exposed so that the user can write or stamp the necessary information thereon; the top wall 35 of the insert-member 34 providing a relatively firm supporting surface during the writing operation.

After the label has been marked, it is moved, by finger pressure, to the position shown in dash-dot lines in Figure 1, wherein its line of perforations 40 is in alignment with the lip 43 so that an upward tearing pull upon the label will result in its being severed from the roll preparatory to being affixed to a container or the like.

At the same time, the next label is positioned within the window 22 so that it, in turn, is ready to be written upon or stamped.

Optionally, some or all of the eight fold-lines intervening the walls 21, 23, 24, 25 and 26 may be provided with lightweight metal reinforcing strips 45 each bent at right angles along a longitudinal line 46 so as to overlie and fit snugly upon the fold-line of the box. A plurality of small inwardly-extending fastening prongs 47 are integrally struck out from each of the strips 45 and penetrate the wall of the box 20 in the manner indicated particularly in Figure 2 so as to secure the strip 45 into the box 20.

The metal reinforcing strips 45 add considerably to the strength of the box or container 20 and are particularly desirable where the box contains a large roll of labels so that it will be in use for a relatively long period of time.

From the foregoing description, it is readily apparent that the embodiment shown in Figures 1-4 provides a simple inexpensive and compact vendible dispensing container for a roll of gummed labels or the like which will expose each individual label, successively, in a window, with a relatively secure underlying supporting surface, so that the label can be written upon or stamped conveniently and which will enable the so-marked label to be manually ejected and readily severed from the roll. Since the top wall 35 of the insert-member 34 underlies and fits snugly against the underside of the window 22, the roll 38 of labels is fully enclosed, except for the label to be disposed and, in this way, the roll is protected from dirt, moisture, etc.

In another embodiment of the present invention, shown in Figures 5-9, I may provide a one-piece box or container 50 having a top wall 51, side walls 52, 53 and 54, a bottom wall 55 and a cover or lid 56; the cover or lid 56 being formed in continuation of the side wall 52 and having a vertical hinge-line 57. While the box or container 50 is shown in the drawing as being in the form of a cube, with square sides formed at right angles to each other, the invention is not limited to a cubic form and, instead, the shape of the walls may be varied as desired.

As shown particularly in Figures 6-8, the top and bottom walls 51 and 55 may be provided with flaps 58, disposed inside of, and adhesively secured to, the side walls 52 and 54 so as to provide a generally enclosed structure.

Flaps 59 and 60 may be provided at the free edges of the top and bottom walls 51 and 55, respectively, while a flap 61 may be provided upon the free edge of the side wall 54. A slit 62 may be formed in the flap 61 so as to receive and frictionally retain a tongue 63 formed on the free vertical edge of the cover or lid 56.

As is evident from Figure 8, the box 50 is closed by first folding in the flaps 59 and 60 and then folding in the flap 61 and finally closing the cover or lid 56 and inserting the tongue 63 into the slit 62.

As shown particularly in Figure 9, the top wall 51 is provided with a slot 64 extending parallel to and spaced slightly inwardly from the free edge of said top wall 51.

A pair of elongated side retaining-flaps 65 and 66 are integrally struck out of the top wall 51 so that they extend in parallel spaced relationship to each other and generally at right angles to the slot 64.

A roll 38 of individual gummed labels 39 separated by lines of perforations 40 is inserted within the box 50 with its free end emerging from the slot 64; the endmost label extending across and above the top wall 51 with the retaining-flaps 65 and 66 overlying the side edges of the label as indicated particularly in Figures 5, 6 and 7.

With the endmost label in position shown in solid lines in Figure 5, it is supported by the top wall 51 so that it can be written upon or stamped, after which it can be moved manually, by finger pressure, to the position shown in dash-dot lines in Figure 5 wherein it can be torn off. The ends of the retaining-flaps 65 and 66 are provided with small outwardly-directed cutting edges 67 and 68 which serve to initiate the severing of the perforation line when the ejected label is pulled upward.

The positioning of the slot 64 adjacent the open side of the box or container 50 facilitates insertion of the free end of the roll within the slot, preliminary to closing of the cover or lid 56.

In this embodiment, metal reinforcing strips 45 similar to those described hereinabove may be provided for the fold-lines intervening the walls 51-53, 52-53, 54-53, 55-53, 52-55, and 54-55. The fold-lines intervening the walls 51-52 and 51-54 are without metal reinforcing strips in the embodiment shown in the drawing since these would overlie the retaining-flaps 65 and 66. However, it is apparent that, by making the box slightly oversize with respect to the transverse dimension of the labels in the roll 38, the fold-lines intervening the walls 51-52 and 51-54 can be provided with metal reinforcing strips 45; the retaining-flaps 65 and 66 being formed inwardly of the strips.

In Figures 10-13, there is shown another embodiment of the present invention comprising a one-piece box or container 70 having a top wall 71, side walls 72, 73 and 74, a bottom wall 75 and a cover or lid 76 formed in continuation of the top wall 71 and provided with a horizontal hinge-line 77 disposed somewhat below the uppermost edge of said cover or lid 76. The top and bottom walls 71 and 75 may be provided with flaps 84 disposed inside of, and adhesively secured to, the side walls 72 and 74 so as to form a generally enclosed structure. As will be evident to those skilled in the art, the box 70 (as well as the boxes 20 and 50 of the embodiments de-

scribed hereinabove) can be provided with various other types of flaps for the purpose of forming a generally enclosed structure.

The lower end of the cover or lid 76 is provided with an insert flap or tongue 78 for frictionally retaining it in closed position as indicated particularly in Figure 12.

A slot 79 is formed in the top wall 71 generally parallel to but spaced somewhat inwardly from the fold-line intervening the top wall 71 and the cover or lid 76. A parallel slot 80 is formed in the top wall 71 somewhat inwardly from the fold-line separating the top wall 71 from the side wall 73.

The side wall 73 is provided with a slot 81 generally parallel to and spaced somewhat below the fold-line intervening the walls 73 and 71.

Metal reinforcing strips 45 similar to those described hereinabove are provided along the fold-lines intervening the walls 71-72, 71-74, 72-75, 74-75, and 73-75. A similar metal reinforcing strip 45 is provided upon the fold-line intervening the top wall 71 and the cover or lid 76. The hinge-line 77 is positioned just below the reinforcing strip 45 while the slot 79 is positioned just inward of said reinforcing strip 45, as indicated particularly in Figures 11 and 12 so that the reinforcing strip does not interfere with the functions of said hinge-line and slot.

A modified metal reinforcing strip 82 having a slightly outwardly bent straight shearing-edge 83 is provided upon the fold-line intervening the top wall 71 and the side wall 73. The shearing-edge 83 of the reinforcing strip 82 extends downward somewhat beyond the slot 80 as indicated particularly in Figure 12.

A roll 38 of individual gummed labels 39 separated by transverse lines of perforations 40 is inserted within the box or container 70 and its free end is passed upward through the slot 79, across the top wall 71, and downward through the slot 80, from which it passes diagonally to and out of the slot 81, as indicated in Figure 12.

The end label is thus positioned above the top wall 71, as shown in solid lines in Figure 10 so that it can be written upon or stamped. The so-marked end-label can then be moved manually by finger pressure, to the position shown in dash-dot lines in Figure 10 wherein its line of perforations is in alignment with the shearing-edge 83 so that an upward pull upon the label will tear it off.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent:

1. A vendable dispensing container for a roll of individually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, retaining means for holding the exposed endmost label in generally horizontal overlying relationship to the top wall whereby the endmost label can be written upon or stamped and can thereafter be moved horizontally by finger pressure to ejected position, thereby simultaneously moving the next label to exposed position ready to be written upon or stamped, and severing means adjacent the opposite edge of the top wall for severing the ejected label from the remainder of the roll.

2. A vendable dispensing container for a roll of indi-

vidually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, retaining means for holding the exposed endmost label in generally horizontal overlying relationship to the top wall whereby the endmost label can be written upon or stamped and can thereafter be moved horizontally by finger pressure to ejected position, thereby simultaneously moving the next label to exposed position ready to be written upon or stamped, said retaining means including a pair of side retaining flaps integrally struck out of the top wall and extending generally at right angles to said slit and constructed and arranged to fit over the side edges of the exposed endmost label and to hold it snugly against the upper surface of the top wall, and severing means disposed adjacent the opposite edge of the top wall for severing the ejected label from the remainder of the roll.

3. A vendable dispensing container for a roll of individually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, retaining means for holding the exposed endmost label in generally horizontal overlying relationship to the top wall whereby the endmost label can be written upon or stamped and can thereafter be moved horizontally by finger pressure to ejected position, thereby simultaneously moving the next label to exposed position ready to be written upon or stamped, said retaining means including a pair of side retaining flaps integrally struck out of the top wall and extending generally at right angles to said slit and constructed and arranged to fit over the side edges of the exposed endmost label and to hold it snugly against the upper surface of the top wall, and cutting edges formed at the ends of said retaining flaps adjacent the opposite edge of said top wall, whereby the ejected endmost label can be severed from the remainder of the roll.

4. A construction according to claim 3 in which the hinged cover forms one of the side walls of the box in which the first slit is formed adjacent the edge of the top wall adjoining the cover.

5. A vendable dispensing container for a roll of individually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, a second slit formed in the top wall spaced somewhat inwardly from and extending generally parallel to the opposite edge of said top wall, said box having a third slit formed in one of its side walls, generally parallel to and spaced somewhat below the last-mentioned edge of the top wall, whereby the major portion of the endmost label extends generally horizontally across the top wall in exposed supported position so that

it can be written upon or stamped and whereby the free end of said endmost label can pass into the second slit and out of the third slit, said endmost label being constructed and arranged to be moved by finger pressure, after being written upon or stamped, to fully ejected position wherein its protrudes fully beyond the third slit, thereby to pull the next label into exposed position above the top wall, the fully ejected label being constructed and arranged manually to be severed from the remainder of the roll.

6. A vendable dispensing container for a roll of individually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, a second slit formed in the top wall spaced somewhat inwardly from and extending generally parallel to the opposite edge of said top wall, said box having a third slit formed in one of its side walls, generally parallel to and spaced somewhat below the last-mentioned edge of the top wall, whereby the major portion of the endmost label extends generally horizontally across the top wall in exposed supported position so that it can be written upon or stamped and whereby the free end of said endmost label can pass into the second slit and out of the third slit, said endmost label being constructed and arranged to be moved by finger pressure, after being written upon or stamped, to fully ejected position wherein it protrudes fully beyond the third slit, thereby to pull the next label into exposed position above the top wall, and severing means disposed adjacent the third slit whereby the fully ejected label can be manually severed from the remainder of the roll.

7. A vendable dispensing container for a roll of individually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, a second slit formed in the top wall spaced somewhat inwardly from and extending generally parallel to the opposite edge of said top wall, said box having a third slit formed in one of its side walls, generally parallel to and spaced somewhat below the last-mentioned edge of the top wall, whereby the major portion of the endmost label extends generally horizontally across the top wall in exposed supported position so that it can be written upon or stamped and whereby the free end of said endmost label can pass into the second slit and out of the third slit, said endmost label being constructed and arranged to be moved by finger pressure, after being written upon or stamped, to fully ejected position wherein it protrudes fully beyond the third slit, thereby to pull the next label into exposed position above the top wall, and severing means disposed adjacent the third slit whereby the fully ejected label can be manually severed from the remainder of the roll, said severing means comprising an elongated longitudinally-folded thin reinforcing strip of metal or the like fastened to the box in overlying relationship to the fold-line intervening the second and third slits, said reinforcing strip having a lowermost generally horizontal severing edge disposed generally in alignment with the third slit.

8. A vendable dispensing container for a roll of in-

dividually severable gummed labels or the like, said container comprising a generally rectangular six-sided box having a top wall, four side walls and a bottom wall, one of said walls constituting a hinged cover for the box, said box being constructed and arranged snugly to hold a roll of individually severable gummed labels or the like with the axis of the roll disposed generally horizontally, said top wall having a transverse slit formed therein somewhat inwardly from and generally parallel to one of its edges, whereby the endmost label of the roll can emerge from the box, a second slit formed in the top wall spaced somewhat inwardly from and extending generally parallel to the opposite edge of said top wall, said box having a third slit formed in one of its side walls, generally parallel to and spaced somewhat below the last-mentioned edge of the top wall, whereby the major portion of the endmost label extends generally horizontally across the top wall in exposed supported position so that it can be written upon or stamped and whereby the free end of said endmost label can pass into the second slit and out of the third slit, said endmost label being constructed and arranged to be moved by finger pressure, after being written upon or stamped, to fully ejected position wherein it protrudes fully beyond the third slit, thereby to pull the next label into exposed position above the top wall, and severing means disposed adjacent the third slit whereby the fully ejected label can be manually severed from the remainder of the roll, said severing means comprising an elongated longitudinally-folded thin reinforcing strip of metal or the like fastened to the box in overlying relationship to the fold-line intervening the second and third slits, said reinforcing strip having a downwardly-extending outwardly-flared portion with a lowermost severing edge disposed generally in alignment with but spaced slightly outwardly from said third slit.

9. A construction according to claim 8 wherein the hinged cover forms one of the side walls of the box and wherein the first slit is formed in the edge of the top wall adjoining the hinged cover.

10. A vendable dispensing container for a roll of individually severable gummed labels or the like, said container comprising a generally rectangular six-sided box having a top wall, four side walls and a bottom wall, one of said side walls constituting a hinged cover for the box, said cover having a vertical hinge-line, said box being constructed and arranged snugly to hold a roll of individually severable gummed labels or the like with the axis of the roll disposed horizontally, said top wall having a window formed therein, said window occupying a major portion of the area of the top wall surface, a transverse dispensing opening extending along the edge of said top wall adjacent said cover, a generally U-shaped insert-member having a top wall and side walls fitting snugly within the box, the axial ends of the roll of gummed labels fitting snugly against the side walls of the insert-member, the top wall of the insert-member fitting snugly against the underside of the top wall of the box, in underlying relationship to said window, the endmost label of the roll of the gummed labels being constructed and arranged to extend horizontally intermediate the top wall of the box and the top wall of the insert-member with the major portion of said endmost label exposed within said window whereby said endmost label can be written upon or stamped, the marked endmost label being thereafter movable by finger pressure to ejected position wherein it extends fully beyond the dispensing opening and can be torn off, the ejection of the marked endmost label serving to bring the next label into exposed position relative to the window.

11. A vendable dispensing container for a roll of individually severable gummed labels or the like, said container comprising a generally rectangular six-sided box having a top wall, four side walls and a bottom wall, one of said side walls constituting a hinged cover for the box, said cover having a vertical hinge-line, a plurality

of elongated longitudinally-bent lightweight metal reinforcing strips affixed to the box in overlying relationship to some of the fold-lines intervening said walls, said box being constructed and arranged snugly to hold a roll of individually severable gummed labels or the like with the axis of the roll disposed horizontally, said top wall having a window formed therein, said window occupying a major portion of the area of the top wall surface, a transverse dispensing opening extending along the edge of said top wall adjacent said cover, a generally U-shaped insert-member having a top wall and side walls fitting snugly within the box, the axial ends of the roll of gummed labels fitting snugly against the side walls of the insert-member, the top wall of the insert-member fitting snugly against the underside of the top wall of the box, in underlying relationship to said window, the endmost label of the roll of the gummed labels being constructed and arranged to extend horizontally intermediate the top wall of the box and the top wall of the

insert-member with the major portion of said endmost label exposed within said window whereby said endmost label can be written upon or stamped, the marked endmost label being thereafter movable by finger pressure to ejected position wherein it extends fully beyond the dispensing opening and can be torn off, the ejection of the marked endmost label serving to bring the next label into exposed position relative to the window.
